UNITED STATES PATENT OFFICE.

FREDERICK A. BARTLETT AND RALPH J. DAVIS, OF BOISE, IDAHO, ASSIGNEES OF
ONE-THIRD TO ROBERT M. McCACKEN, OF BOISE, IDAHO.

BRIDGE SCORER.

Application filed September 24, 1925. Serial No. 58,333.

The present invention relates to a score calculation particularly designed for use in connection with playing cards.

The present embodiment of the invention discloses an arrangement which will enable players to quickly and accurately determine the value of a hand or game of bridge.

More specifically the device includes a score card having printed on both its faces data indicating the varying values of different hands of bridge, the data being so arranged as to permit the use of an adjustable indicating member, the latter also carrying data such as will, by proper adjustment in conjunction with the card, assist a player in making his calculations.

To more clearly indicate the use and operation of the present invention, the upper portion of both faces of the score card contains printed instructions both in the use of the scoring device and in the rules of the game in question.

To more clearly illustrate the invention, reference will be had to the accompanying drawings forming a part of this specification and wherein like numerals designate corresponding parts throughout the several views, in which,

Figure 1 is a top plan view of the front face of the score card showing the sliding indicator in position with parts broken away,

Figure 2 is a plan view of the back face of the score card,

Figure 3 is a plan view of the front side of the sliding indicator and

Figure 4 is a top plan of the indicator member.

Referring now to Figure 1, the front face of the score card is shown to include an upper space A containing instructions to a player both as to the use of the slide hereinafter mentioned and also information in connection with the data compiled in the lower space B. Intermediate the spaces A and B is the group of figures C indicating the basic value of the various hands before the addition of extra points. Both spaces B and C are partitioned by spaced vertical and horizontal lines into a plurality of squares or sections for grouping the data indicating card or hand values. In the present illustration the varying values of a definite hand are arranged in the horizontal groups of squares or sections with the key data in the last square or section indicated

by reference characters b and c. The values are arranged to increase from left to right across the card as such arrangement has been found to be more practical and natural to a player when using same.

The slide member D shown in detail in Figures 3 and 4, comprises two similar sections d of cardboard or other suitable material, spaced by end blocks d' to permit the free movement of the score card therebetween. The sections d' are slotted as at d'' to form windows through which the registering data on the score card may be read. Attention is called to the fact that the portions of the slide is on both its faces printed with similar data arranged to be read in connection with that data printed on the score card in both horizontal and vertical groups.

The reverse side of the score card illustrated in Figure 2 includes the upper space or surface section E and the lower section F. The upper section E includes printed matter in the form of information and instructions and the lower section F being a continuation of section B of the front face of the score card, both as to arrangement and data.

With reference to the printed matter shown on the present drawing, it will be seen that same comprises figures indicating complete hand values for each card according to the bid, extra points also being computed and included. These figures are arranged in a manner both convenient and practical to permit quick calculations under all circumstances without the necessity of mental mathematical variations, and give every possible score as well as the totals thereof.

It will be obvious to one familiar with the art that this invention can be manufactured either from cardboard, paper or from a more permanent and expensive material. In addition, the size could be varied if necessary for enclosing in the conventional package of playing cards.

What we claim as new and useful and desire to secure by Letters Patent is:

1. In a bridge scorer, a card having instructions at the upper end of each face, a table arranged on both sides therebelow presenting each possible bridge score the multiplied and added totals of the several possible scores, means for immediately locating

a desired score and total comprising a slide including a pair of spaced members arranged to straddle and conceal a small part only of said card, registering apertures for permitting inspection of a located score, and data printed on said slide for use in conjunction with each score.

2. In a bridge scorer, a card having printed on each side thereof, complete scores for a bridge hand, and indicia adjacent thereto for locating a desired score, in combination with a slide shorter than said card, and including a pair of spaced members arranged to straddle and conceal a part of said card, an aperture in each member permitting inspection of a located score and its adjacent indicia, and data printed on each member for use in conjunction with each score.
3. In a bridge scorer, a card having a table arranged on each of its faces, the table on the rear face being a continuation of the table on the front face, said tables

presenting each possible bridge score, the multiplied and added totals of the several possible scores, each table consisting of vertical columns of figures and a vertical trump column adjacent the same, said columns being separated transversely to provide horizontal rows, each row containing a plurality of groups of figures applying to the score, doubled and redoubled, and means for immediately locating a desired score and total comprising a slide including a pair of spaced members arranged at opposite sides of the card, each member having a window of the same size as each of said horizontal rows, and data printed on each member cooperating with said columns and rows to permit all possible bridge score calculations to be arrived at by a single operation.

In testimony whereof we affix our signatures.

FREDERICK A. BARTLETT.
RALPH J. DAVIS.
